CLAIM

The ornamental design for a hanging bauble-pot, as shown and described.

DESCRIPTION

FIG. 1 is a perspective view of a hanging bauble-pot, showing my new design;

FIG. 2 is a right-side elevational view thereof;

FIG. 3 is a left-side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines showing a suspension wire in FIGS. 1-5 depict environmental matter and form no part of the claimed design.

1 Claim, 4 Drawing Sheets(56)
